UNITED STATES PATENT OFFICE

93,352

DESIGN FOR A CONTROL HEAD FOR A RADIORECEIVER

Donald H. Mitchell, Chicago, Ill., assignor to
Galvin Manufacturing Corporation, Chicago,
Ill., a corporation of Illinois

Application June 4, 1934, Serial No. 52,053

Term of patent 3½ years

To all whom it may concern:

Be it known that I, DONALD H. MITCHELL, a citizen of the United States, residing at Chicago, Illinois, post office address 847 West Harrison Street, Chicago, Illinois, have invented a new, original, and ornamental Design for a Control Head for a Radio Receiver, of which the following is a specification, reference being had to the accompanying drawing, forming part thereof.

Fig. 1 shows a perspective view of my new design for a control head for a radio receiver, and Fig. 2 is a top plan view thereof.

I claim:

The ornamental design for a control head for a radio receiver as shown.

DONALD H. MITCHELL.
